Des. 224,386

Patented July 25, 1972

224,386

BATHING CAP

Philip Allen Wilson-Haffenden, Deal, England, assignor
to W. W. Haffenden Limited

Filed July 10, 1970, Ser. No. 23,904

Claims priority, application Great Britain Apr. 22, 1970

Term of patent 14 years

Int. Cl. D2—03

U.S. Cl. D2—237

The figure is a side elevational view of a bathing cap showing my new design, the surface configuration shown being an overall decoration on both sides of the bathing cap and as indicated, portions of the surface configuration having been omitted for convenience of illustration.

I claim:

The ornamental design for a bathing cap, as shown and described.
